LIFESAVING EQUIPMENT FOR SUBMARINES

Frank Sheplin and George Macchianich,
Jersey City, N. J.

Application April 24, 1935, Serial No. 17,941

16 Claims. (Cl. 114—16.7)

This invention relates to improved life saving equipment for use in submarines, to enable the crew or others to escape to the surface of the water, in which the vessel may be disabled, and to control the velocity or movement from the submarine, so as to insure a safe escape:

Another object of the invention is the provision of an escape equipment for submarines, which will enable groups to successively enter protected buoyant cars within the submarine, and then to release these cars from controlled operations within the cars, so that they can rise from the submarine, under controlled upward movement.

15 A further object of the invention is to provide an escape equipment for submarines, including a tunnel enclosed by the vessel and having its outlet end located in line with a conning tower, or other similar vertical shaft, and means for 20 locking the outlet from the escape tunnel, which can be operated by air pressure to permit of the release of the crew cars working within the tunnel.

A still further object of the invention is the provision of means for admitting water from the exterior of the vessel, to produce equal internal pressure within the tunnel, and to float the crew cars into discharging line position with the conning tower or other entrance shaft of the vessel.

30 A still further object of the invention is the provision of means for unlocking the hatch cover or closure, by the use of compressed air and a connection for the cover, which will permit of the forcible discharge of the cover from the vessel.

A still further object of the invention is the provision of a speed control arrangement equipped on and operable within the escape car.

35 A still further object of the invention is to provide means for locking the crew cars to the tunnel, which will permit the crew to enter the car and then disconnect the same from the tunnel, while sealing the car against external water pressure, and then to propel the car in the tunnel into line position with the tunnel outlet to the external waters.

With the above and other objects in view, the invention consists in certain new and useful constructions, combinations and arrangements of parts, clearly described in the following specification, and fully illustrated in the accompanying drawings, in which:

Fig. 1 is a side view of a submarine, with a portion broken away and showing the tunnel in section.

Fig. 2 is a detail vertical sectional view through the conning tower, on an enlarged scale, showing the closure lock and the pressure operated release therefor.

Fig. 3 is a detail vertical sectional view of a 5 sliding pipe coupling for the pressure feed pipe of the closure lock.

Fig. 4 is a detail vertical sectional view through the tunnel, on an enlarged scale, partly in section and partly in elevation.

10 Fig. 5 is a vertical sectional view, taken on line 5—5 of Fig. 4, looking in the direction of the arrows.

Fig. 6 is a detail vertical sectional view, taken on line 6—6 of Fig. 4, looking in the direction of 15 the arrows.

Fig. 7 is an enlarged fragmentary view of a portion of Fig. 5.

Fig. 8 is a vertical fragmentary sectional view of the bottom portion of an escape car 20 constructed according to a modified form of the invention.

Fig. 9 is a horizontal sectional view taken on the line 9—9 of Fig. 8.

Referring to the accompanying drawings illustrating the practical construction of our improved submarine escape system, 5 designates a submarine, which is equipped with a conning tower 6, providing a vertical shaft 7 for the escape tunnel 8, which is arranged at a rising inclination within the vessel, the tunnel and the shaft forming an L-shaped passage. An additional conning tower shaft 9 may be provided, to afford a separate entrance and exit for the submarine.

35 In the upper end of the conning tower shaft 7 the cover or closure 10 is tightly fitted, by means of the tapered hollow body 10^a. This body is formed hollow so that it will be buoyant. The body 10^a is formed with an annular shoulder 10^b, which engages the annular shoulder 7^a of the 40 shaft 7. Below this shoulder the locking bolts 11 and 12 work. The outer ends of these rods are tapered and slide into and out of the sockets 11^a and 12^a formed in the wall of the conning tower shaft. The inner end of the bolt rod 11 is 45 equipped with a piston head 13 and the inner end of the bolt rod 12 is equipped with a piston head 14. These piston heads work in the cylinder 15, which is equipped with a relief valve 16, opening above the cover. Pressure fluid is admitted to 50 the cylinder 15 against the outer side of the piston head 13 by means of the pipe 17, and pressure fluid is admitted to the cylinder against the outer end of the piston head 14 by means of the pipe 18. The two pipes 17 and 18 are coupled to 55

- the pressure pipe 19, which is provided on one end with the branch 20, which is fitted in the vertical pipe 21, and sealed in place by the packing gland 22, threaded in said pipe.
- 5 The lower end of the tunnel is closed by the wall 23, and above this wall the tunnel is equipped with a series of man openings 24, located on opposite sides thereof, and spaced apart from each other in opposed pairs, of suitable area.
- 10 In the tunnel a series of cars 25 is arranged. Each car is provided with side walls 26 and 27, which are provided with man openings 26^a and 27^a, adapted to register with the adjacent pair of man openings 24.
- 15 Screw bolts 28 are provided on each side of the car for coupling the same to the side walls of the tunnel, outside of the man openings, and to seal these openings packing 29 is provided between the car and the tunnel walls. A cover 30 is attached
- 20 on the tunnel over each of its man openings, and another cover 31 is attached on the car over each of its man openings. The screw bolts 28 are provided with cranks adapted to be operated from the inside of the car.
- 25 The side walls of the tunnel are equipped with gear racks 33 and 34 on opposite sides thereof, which are engaged by the gears 33^a and 34^a carried by the ends of the cross shaft 35, mounted to turn in the car, and provided with crank throws 35^a and 35^b, to permit of manual operation by the crew. The gear racks extend toward the shaft of the conning tower. Each car is equipped with a base wheel or roller 36 on each side corner thereof, so that it will roll upwardly.
- 30 Before the crew enters the tunnel man openings, the water control valve 37 is manually operated by the crew; this will admit water to the tunnel and create within the tunnel pressure conditions equal to those outside of the vessel.
- 35 The next operation is for the crew to enter one or all of the cars through the tunnel man openings and through the car openings. After the crew enters the car or cars the car openings are sealed from within the car, by clamping the
- 40 covers thereof in place. When this has been accomplished the screw bolts 28, equipped with cranks are operated, so that the cars are disconnected from the tunnel.
- 45 When the water enters the tunnel from the outside of the submarine, it cannot enter the cars, and compresses air in the conning tower under the cover thereof. This compressed air is utilized to operate the piston released bolts of the cover, controlled by means of the manual valve 40, located outside near the lower end of the tunnel. The air from the tunnel enters pipe 40^a, passes through the valve 40, then along the pipe 21, the pipe 19, and the pipes 17 and 18 to move the pistons.
- 50 This will release the cover, which will be blown upwardly by reason of the combined forces developed by the buoyancy of the cover and the internal pressure against the cover. Additional air pressure may be supplied the conning tower shaft
- 55 by means of the compressed air supply of the vessel. The rising of the cover will cause the branch pipe of the cover to be forcibly withdrawn from the feed pipe, at the connection as shown in Fig. 3 or the pipes will bend or break,
- 60 or connections thereof will turn. With nothing now to restrain the cover it will be completely pivoted from or detached from the top of the tower and the cars can discharge successively through the open conning tower, when uncoupled
- 65 and 25' may also be stored in the vertical shaft 7 in place of the inclined tunnel 8.
- 70 While we have illustrated and described the preferred embodiment of our invention, it is to be understood that we do not limit ourselves to the 70 precise construction herein disclosed, and the right is reserved to all changes and modifications coming within the scope of the invention as defined in the appended claims.

In order to control the speed of the vertical movement of the cars to the surface, each car is equipped with a vertical water conduit 42, which opens through the top wall of the car, and which communicates with the dome or distributor 43 at 5 the bottom of the car. The flow of water through this distributor is controlled by means of the conical valve 44, which is operated by means of the worm shaft 45, which engages the worm gear 47 on screw shaft of the valve. The outer end 10 of the worm shaft 45 is enclosed within the car and may be operated by the crew.

The distributor opens through the bottom of the car, and by regulating the volume of water flowing through the car, the resistance of the car 15 to vertical movement may be modified, and the ballasting effect on the car controlled.

Ballast tanks 48 are mounted on the sides of the car and are adapted to store up oxygen.

It will be seen that access to each of the cars 20 is made absolutely safe and easy, and that when once installed in a car all operations required to release the car take place in proper order. When the car reaches the upper end of the conning tower shaft it will engage a plunger 49 resiliently 25 maintained in a lower position, and force the plunger upwards.

The stem 50 of the plunger 49 is formed with rack teeth 50' meshing with a pinion 51 mounted upon a spindle 52 rotatively supported in the 30 chamber 15. A disc 53 is mounted upon the spindle 52 and eccentrically connects with the inner ends of rods 54 which are pivotally connected at their other ends with the pistons 13 and 14. An expansion spring 55 normally urges the plunger 35: 59 into the lowered position.

The arrangement is such that should the pneumatic or hydraulic means fail to retract the bolts 11 and 12, when the first car reaches the top of the tower it will strike the plunger 49 and force 40 it upwards and cause the disc 53 to partially turn and draw the rods 54, the pistons 13 and 14, and the bolts 11 and 12 from their latching positions.

In Figs. 8 and 9 another form of the invention 45 is illustrated. In this form the escape car 25' is shown to be cylindrical and is provided with a pair of split ring sections 25^a and 25^b joined by slidably guiding pins 25^c. The outer face of ring sections 25^a and 25^b is normally flush with the 50 outer periphery of the escape car 25'. These ring sections may be used as a brake to control the speed of motion of the escape car by turning the threaded bar 55 by its operating crank handle 56 located at one side of the said bar. The 55 threaded bar 55 engages the corresponding threaded boss 57 secured to the inner side of the escape car 25'. A flange 58 at the other side of the threaded bar 55 is rotatively secured to the ring section so that upon rotation of crank handle 56, the center of the ring section is radially moved away from the center of the escape car toward the inner periphery of escape tunnel 8 and vertical shaft 7.

It is to be understood that the escape cars 25 65 and 25' may also be stored in the vertical shaft 7 in place of the inclined tunnel 8.

While we have illustrated and described the preferred embodiment of our invention, it is to be understood that we do not limit ourselves to the 70 precise construction herein disclosed, and the right is reserved to all changes and modifications coming within the scope of the invention as defined in the appended claims.

Having thus described our invention, what we 75

claim as new, and desire to secure by United States Letters Patent is:—

1. In combination with a submarine having a tower, an escape tunnel communicating with the interior thereof and terminating in the tower having a releasably closed top, water-proof cars in said tunnel, water-proof means for providing access to the interiors of said cars from the interior of the submarine, means for controlling the entrance of water into said tunnel, means for opening the top of said tower, and means for assisting said cars through the tunnel and out from said tower, said tunnel and tower being substantially of L-shape with the tower corresponding with the vertical arm of the L form, and the tunnel with the horizontal arm, said horizontal arm being arranged at an inclination so that the cars may travel upwards through the tunnel into the tower.

2. In combination with a submarine having a tower, an escape tunnel communicating with the interior thereof and terminating in the tower having a releasably closed top, water-proof cars in said tunnel, water-proof means for providing access to the interiors of said cars from the interior of the submarine, means for controlling the entrance of water into said tunnel, means for opening the top of said tower, and means for assisting said cars through the tunnel and out from said tower, said water-proof means for providing access into the interior of the cars from the interior of the submarine, comprising a plurality of manholes in the cars and in the tunnel aligning with each other, means for closing said manholes, means for connecting the cars and the tunnel so that the manholes constitute a water-proof passage from the submarine through the tunnel into the cars.

3. In combination with a submarine having a tower, an escape tunnel communicating with the interior thereof and terminating in the tower having a releasably closed top, water-proof cars in said tunnel, water-proof means for providing access to the interiors of said cars from the interior of the submarine, means for controlling the entrance of water into said tunnel, means for opening the top of said tower, and means for assisting said cars through the tunnel and out from said tower, said water-proof means for providing access into the interior of the cars from the interior of the submarine, comprising a plurality of manholes in the cars and in the tunnel aligning with each other, means for closing said manholes, means for connecting the cars and the tunnel so that the manholes constitute a water-proof passage from the submarine through the tunnel into the cars, water-proof annular members being disposed between the walls of the tunnel and the car surrounding said manholes.

60 4. In combination with a submarine having a tower, an escape tunnel communicating with the interior thereof and terminating in the tower having a releasably closed top, water-proof cars in said tunnel, water-proof means for providing
65 access to the interiors of said cars from the interior of the submarine, means for controlling the entrance of water into said tunnel, means for opening the top of said tower, and means for assisting said cars through the tunnel and out
70 from said tower, said water-proof means for providing access into the interior of the cars from the interior of the submarine, comprising a plurality of manholes in the cars and in the tunnel aligning with each other, means for closing said
75 manholes, means for connecting the cars and the

tunnel so that the manholes constitute a water-proof passage from the submarine through the tunnel into the cars, water-proof annular members being disposed between the walls of the tunnel and the car surrounding said manholes, and screws holding the walls of the car and tunnel together to clamp the water-proof material into operative positions.

5. In combination with a submarine having a tower, an escape tunnel communicating with the 10 interior thereof and terminating in the tower having a releasably closed top, water-proof cars in said tunnel, water-proof means for providing access to the interiors of said cars from the interior of the submarine, means for controlling 15 the entrance of water into said tunnel, means for opening the top of said tower, and means for assisting said cars through the tunnel and out from said tower, said water-proof means for providing access into the interior of the cars 20 from the interior of the submarine, comprising a plurality of manholes in the cars and in the tunnel aligning with each other, means for closing said manholes, means for connecting the cars and the tunnel so that the manholes constitute 25 a water-proof passage from the submarine through the tunnel into the cars, water-proof annular members being disposed between the walls of the tunnel and the car surrounding said manholes, and screws holding the walls of the 30 car and tunnel together to clamp the water-proof material into operative positions, said screws having handles within the car by which the car may be released from the tunnel.

6. In combination with a submarine having a 35
tower, an escape tunnel communicating with the
interior thereof and terminating in the tower
having a releasably closed top, water-proof cars
in said tunnel, water-proof means for providing
access to the interiors of said cars from the in- 40
terior of the submarine, means for controlling the
entrance of water into said tunnel, means for
opening the top of said tower, and means for
assisting said cars through the tunnel and out
from said tower, said means for controlling the 45
entrance of water into the tunnel comprising a
pipe extending from the exterior of the sub-
marine into the lower portion of the tunnel and
controlled with a valve.

7. In combination with a submarine having a 50
tower, an escape tunnel communicating with
the interior thereof and terminating in the tower
having a releasably closed top, water-proof cars
in said tunnel, water-proof means for providing
access to the interiors of said cars from the in- 55
terior of the submarine, means for controlling the
entrance of water into said tunnel, means for
opening the top of said tower, and means for
assisting said cars through the tunnel and out
from said tower, said means for opening the top 60
of the tower comprising slidable bolts engaging
a cover over the top of the tower and the walls
of the tower, and air operated means for moving
said bolts when water enters the tunnel and
air at the top of the tower consequently is forced 65
under pressure.

8. In combination with a submarine having a tower, an escape tunnel communicating with the interior thereof and terminating in the tower having a releasably closed top, water-proof cars 70 in said tunnel, water-proof means for providing access to the interiors of said cars from the interior of the submarine, means for controlling the entrance of water into said tunnel, means for opening the top of said tower, and means 75

for assisting said cars through the tunnel and out from said tower, said means for opening the top of the tower comprising slidable bolts engaging a cover over the top of the tower and the walls of the tower, and air operated means for moving said bolts when water enters the tunnel and air at the top of the tower consequently is forced under pressure, said bolts having pistons on one of their ends, and said compressed air being directed to move the pistons so as to move the bolts.

9. In combination with a submarine having a tower, an escape tunnel communicating with the interior thereof and terminating in the tower having a releasably closed top, water-proof cars in said tunnel, water-proof means for providing access to the interiors of said cars from the interior of the submarine, means for controlling the entrance of water into said tunnel, means for opening the top of said tower, and means for assisting said cars through the tunnel and out from said tower, said means for opening the top of the tower comprising slidable bolts engaging a cover over the top of the tower and the walls of the tower, and air operated means for moving said bolts when water enters the tunnel and air at the top of the tower consequently is forced under pressure, and mechanical means for retracting the bolts when and if one of the cars strikes the roof of the tower.

10. In combination with a submarine having a tower, an escape tunnel communicating with the interior thereof and terminating in the tower having a releasably closed top, water-proof cars in said tunnel, water-proof means for providing access to the interiors of said cars from the interior of the submarine, means for controlling the entrance of water into said tunnel, means for opening the top of said tower, and means for assisting said cars through the tunnel and out from said tower, said means for opening the top of the tower comprising slidable bolts engaging a cover over the top of the tower and the walls of the tower, and air operated means for moving said bolts when water enters the tunnel and air at the top of the tower consequently is forced under pressure, and mechanical means for retracting the bolts when and if one of the cars strikes the roof of the tower, comprising a plunger extending downwards from the roof into the tower, and means connecting the plunger and bolts to retract the bolts when the plunger is moved upwards.

11. In combination with a submarine having a tower, an escape tunnel communicating with the interior thereof and terminating in the tower having a releasably closed top, water-proof cars in said tunnel, water-proof means for providing access to the interiors of said cars from the interior of the submarine, means for controlling the entrance of water into said tunnel, means for opening the top of said tower, and means for assisting said cars through the tunnel and out from said tower, comprising stationary racks upon the sides of the tower and engaged by gears upon the extremities of a shaft passing through the car.

12. In combination with a submarine having a tower, an escape tunnel communicating with the interior thereof and terminating in the tower having a releasably closed top, water-proof cars in said tunnel, water-proof means for providing access to the interiors of said cars from the interior of the submarine, means for controlling

the entrance of water into said tunnel, means for opening the top of said tower, and means for assisting said cars through the tunnel and out from said tower, comprising stationary racks upon the sides of the tower and engaged by gears upon the extremities of a shaft passing through the car, said shaft being provided with cranks by which it may be conveniently turned. 5

13. The combination with a submarine having an entrance and exit shaft, of an inclined tunnel arranged in the submarine with one end communicating with the shaft, means for locking the shaft against the admission of water to the tunnel, means for controlling said locking means operable from the other end of the shaft, means co-15 operating therewith for admitting water to the tunnel from the outside of the submarine to produce an internal pressure approximately equal to that of the water outside of the submarine, and means in the tunnel for conveying a person 20 through the tunnel to the shaft and to the outside water when the shaft is opened by the operation of said locking means.

14. The combination with a submarine having a conning shaft providing an entrance to the submarine, of an inclined tunnel communicating at its upper end with the shaft and provided with a closed lower end, means for admitting water to the tunnel from the outside of the submarine, a cover for closing the shaft against the entrance 25 of water thereto, pressure actuated means for locking the cover to the shaft, means controlled at a distance from the cover for operating said pressure actuated means, a series of cars in the tunnel, means formed in the wall of the tunnel 30 providing an entrance to each car, means in each car for closing its own entrance, means for locking each car to the tunnel adapted to seal the entrance thereto against leakage, and means for propelling the car in the tunnel toward the open 40 end of the shaft.

15. The combination with the submarine having a conning shaft providing an entrance to the submarine, of an inclined tunnel communicating at its upper end with the shaft and sealed at its 45 lower end against the admission of water thereto, said tunnel having a man opening in its side, a car within the tunnel having a corresponding man opening in its side, means for closing both sets of openings, means for securing the car to 50 the tunnel, means for closing the upper end of the shaft, means for locking said closing means which is operative from a distance to the shaft, means for admitting water to the tunnel from the outside of the submarine, and means in the 55 car for varying the speed of the upward movement of the car through the water outside of the submarine when released from the submarine.

16. In combination with a submarine having a 60 tower, an escape tunnel communicating with the interior thereof and terminating in the tower having a releasably closed top, water-proof cars in said tunnel, water-proof means for providing access to the interiors of said cars from the interior of the submarine, means for controlling the entrance of water into said tunnel, means for opening the top of said tower, means for assisting said cars through the tunnel and out from said tower, and means for controlling the motion of 65 70 the water proof cars, said means including split friction ring operable from within the said cars.

FRANK SHEPLIN.

GEORGE MACCHIANICH.
